UNITED STATES PATENT OFFICE.

FERDINAND CHARRON AND LÉONCE GIRARDOT, OF PARIS, FRANCE.

VARIABLE-SPEED AND REVERSING-MOTION DRIVING MECHANISM.

SPECIFICATION forming part of Letters Patent No. 737,208, dated August 25, 1903.

Application filed March 22, 1902. Serial No. 99,460. (No model.)

To all whom it may concern:

Be it known that we, FERDINAND CHARRON and LÉONCE GIRARDOT, citizens of the Republic of France, residing at 45 Avenue de la Grande Armée, Paris, in the Republic of France, have invented certain new and useful Improvements in Variable-Speed and Reversing-Motion Driving Mechanisms, of which the following is a specification.

Our invention relates to an improved mechanism for motor-cars by which with a single operating-lever different changes of speed and reversing motion are obtained, this mechanism being remarkable through its simplicity, strength, and suppression of all springs and unnecessary movements. By pushing the lever in one direction the gear passes successively from the highest speed through the various intermediate speeds to the lowest speed and then to the reverse. By moving back the lever in the opposite direction inverse results are obtained. There is thus no useless movement of the lever. The variations of speed are obtained in the usual way by causing the operating-lever to act by means of a gear on a rack, which on displacement draws along the intermediate gear-train, known as the "movable set of gear-wheels," which is submitted to a continuous rotary movement, so as to bring the different gear-wheels of this train successively into mesh with the gear-wheels keyed on the shaft which is to be turned.

The originality of this system lies in the combination with such variable-speed mechanism of a new and extremely simple arrangement for reverse. After the movement of the lever has brought into gear the pinion of the movable set, which gives the smallest forward speed if the lever is pushed farther in the same direction the movable set comes clear of the gears keyed on shaft and are thus out of action. Then the gear of the operating-lever presents to the rack of the movable set a smooth part, so that this rack ceases to be drawn along, and the movable set is rendered stationary in its out-of-gear position. On the axle of operating-lever gear is keyed a second gear, the toothed part of which corresponds with the smooth part of the aforesaid gear, and inversely. At this moment the second gear connects with a second rack, which it draws

along in the opposite direction to that of the first rack, which results in the sliding of a broad auxiliary pinion mounted loose on a supporting-shaft, so that it meshes simultaneously with the low-speed pinion of the movable set and with the corresponding wheel keyed on shaft to be driven. The rotary movement of the movable set is therefore transmitted to the shaft to be driven by means of an interposed pinion, so that this shaft turns in the reverse direction. The reversing motion has thus been produced. When the operating-lever is brought back in the reverse direction, the intermediate pinion is first un-gearred and brought into resting position and the pinions of movable set come successively into gear with the wheels keyed on the shaft to be driven, which gives the forward motion at the desired speed.

The accompanying drawings show the complete mechanism as applied to a motor-car operated through beveled gear and live-wheel axle.

Figure 1 is a vertical section through the shaft to be driven and the shaft of the movable set of gear-wheels. Fig. 2 is an interior plan view of the gear and gear box or case with upper part removed. Fig. 3 is a transverse section on the line A B C D of Fig. 1, showing the part to the left of the section plane. Figs. 4 and 5 represent the details of the gearing mechanism of the racks.

On the drawings, *a* is the motor-driven shaft to which continuous rotary motion is given through the usual clutch. This shaft has a long prismatic part on which can slide the movable set of gear-wheels *b*, which is shown as comprising four gears 1 2 3 4. Above the motor-driven shaft *a* is the shaft *c*, on which four toothed wheels 5, 6, 7, and 8 are fixed. On displacing the movable set the wheels 1 and 5 are first brought into gear and give slow forward speed. Consecutively gears 2 and 6, 3 and 7, 4 and 8 are respectively brought into mesh, giving successively higher speed always for the forward movement. The rotation of shaft *c* is transmitted by beveled wheels to shaft *d*, which may drive the wheels of the car by means of chains. The displacement of the movable set is brought about by the action of the operating-lever, (not shown on drawings,) which is keyed on the transverse

shaft *f*, carrying fixed to it the toothed sector *g*. The toothed sector *g* gears with a pinion *h*, keyed on a shaft *i* and integral with a second pinion *j*, which is in gear with a rack *k*, placed underneath it. An arm *l*, attached to rack *k* and ending in a fork, engages in a groove *m* between collars on the sleeve of the movable set of gears. It will therefore be understood that on pushing the operating-lever in one direction the toothed sector *g* is turned, and by this the rack *k* is moved and with it the sleeve of the movable gear set, so that the different pinions thereof enter successively into gear with the wheels on shaft *c*, which produces the variation of speed. If starting from the high speed, the operating-lever is moved in the reverse direction, the rack *k* is displaced in a corresponding direction, producing successively the corresponding engagement and disengagement of successively slower speeds, arriving at the position illustrated, for which the pinion of the slowest speed 1 leaves the wheel 5. This is the out-of-gear position. Just at this moment the gearing *j*, which works the rack *k* and which has no teeth except at one part of its circumference, presents to this its smooth part, Fig. 4, so that if the operating-lever is pushed farther in the same direction the rack *k*, and in consequence the movable-gear set *b*, is not carried with it; but on the shaft *i*, carrying gearing *j*, is keyed at the other end a second pinion *n*, showing toothed and smooth part in such a way that the toothed part corresponds with the smooth part of gearing *j*, and conversely. Above this gearing *n* is placed a second rack *p*, which can slide longitudinally and which carries an arm in shape of fork *q*, which engages a collar on the hub of a broad auxiliary loose pinion *r* on the shaft *s*. As the rack *p* can gear with the teeth of pinion *n*, if the operating-lever is pushed farther in the same direction after having passed the out-of-gear position the pinion *m* commences to gear with the rack *p*, and this is displaced in the reversed direction, (from right to left in Figs. 2 and 4 of the drawings,) carrying with it the pinion *r*, the dimensions and position of which are such that it can gear simultaneously with the pinion 1 and the wheel 5. The rotation of pinion 1 is therefore transmitted to wheel 5, and therefore to shaft *c* through the medium of the interposed pinion *r*, so that in this way the motion is reversed. On pushing the operating-lever in the other direction the pinion *r* is disconnected from the wheel 5, while 1 and 5, 2 and 6, 3 and 7, and 4 and 8 are then put into gear. The racks *k* and *p* are held in their positions of rest by means of small spring-bolts *t* and *u*, which frictionally engage in notches in the sides of these racks, Fig. 2.

Having now particularly described and ascertained the nature of our said invention and in what manner the same is to be performed, we declare that what we claim is—

1. A variable-speed and reversing-motion driving mechanism comprising two gears with a toothed portion and a smooth portion arranged opposite one to the other, an axle on which said gears are mounted, an operating-lever adapted to drive said axle, two racks the one of which is placed below the first gear and is free to engage the toothed portion of same and the other of which is placed above the second gear and is free to engage the toothed portion of same, a set of gears or movable set adapted to be continually rotated and driven lengthwise on its axle by the first rack, and a broad auxiliary pinion loose on its axle and adapted to be driven lengthwise on said axle by the second rack, substantially as and for the purpose set forth. 75

2. A variable-speed and reversing-motion driving mechanism comprising a shaft *c*, gears 5, 6, 7, 8 mounted on said shaft, a toothed sector *g*, an operating-lever mounted on the axle of said sector, a pinion *h* gearing with the sector, an axle *i* on which said pinion is mounted, a gear *j* having a smooth portion and a toothed portion mounted on the axle *i*, a rack *k* gearing with said gear *j* by its toothed portion and sliding on same by its smooth portion, a set of gears 1, 2, 3, 4, a motor-shaft *a* on which are mounted said gears 1, 2, 3, 4, an arm *l* secured to the rack *k* and adapted to cause the gears 1, 2, 3, 4 to slide on the said motor-shaft *a* and to be brought successively into engagement with gears 5, 6, 7, 8, a second gear *n* mounted on axle *i* and having a smooth portion and a toothed portion, a rack *p* arranged above gear *n* and adapted to gear with its toothed portion, a broad auxiliary pinion *r*, an axle *s* on which said pinion *r* is loosely mounted, an arm *q* secured to the rack *p*, adapted to cause said pinion *r* to slide on its axle and to be brought simultaneously into engagement with gears 1 and 5, substantially as and for the purpose set forth. 105

3. Variable-speed and reversing mechanism comprising a set of driving-gears of different sizes; a set of driven gears of different sizes adapted to mesh therewith; two rack-bars parallel with the axes of the driving and driven gears; connections between one of the racks and one set of gears; a reversing-pinion normally disconnected from the driving and driven gears, and connected with the other of said racks; means for moving one of the racks to shift the set of gears with which it is connected; and devices for shifting the reversing-pinion to cause it to gear with the driving and driven gears after the first-named rack has ceased to move. 110

In witness whereof we have hereunto set 115 our hands in presence of two witnesses.
